2,182,738

ASPARAGUS HOPPER AND BELT

Floyd Phillips, Sandwich, Ill.

Application April 12, 1938, Serial No. 201,620

4 Claims. (Cl. 224—5)

This invention relates to asparagus gathering devices and has for the primary object the provision of a device of this character which is to be worn by a person engaged in cutting asparagus and which will permit a person to have free use of the hands and arms and be free to walk, stand upright and bend over, and which is so constructed that asparagus cut and gathered may be easily stacked therein and retained in the stacked position until removed without danger of damaging or bruising the tender portions of the asparagus.

Another object of the invention is the provision of means for permitting the person to cut the asparagus to a desired length while stacked in the device.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating an asparagus gathering device constructed in accordance with my invention.

Figure 2 is a fragmentary front elevation showing the device strapped on a person.

Figure 3 is a transverse sectional view taken on line 3—3 of Figure 1.

Figure 4 is a longitudinal sectional view taken on line 4—4 of Figure 1.

Referring in detail to the drawing, the numeral 1 indicates a receptacle or hopper fully open at the top thereof and at one end and consisting of a curved bottom wall 2, an end wall 3 and side walls 4 and 5. The side wall 4 is disposed substantially vertically while the side wall 5 inclines upwardly and outwardly with respect to the side wall 4 and from the bottom wall 2. The walls are constructed of sheet metal and the upper edges thereof are bent about a substantially rectangular shaped frame 6 constructed from a single length of material. The length of the frame is greater than the length of the receptacle or hopper so that a portion of the frame will be exposed acting as a handle for the receptacle or hopper. It is preferable that in securing the side wall 4 to the frame said side wall be bent over and inwardly while the side wall 5 is bent over and outwardly of the frame. The end wall 3 is also bent over and outwardly about the frame. The side wall 4 is cut away to expose the frame so that suspension straps 7

and 8 may be connected to the frame and are in turn secured to a waist encircling belt 10. The suspension strap 7 is slightly longer than the suspension strap 8 so that when a belt is placed about a person's waist, as shown in Figure 2, the receptacle or hopper will be supported in an inclined position with the end wall 3 disposed lowermost. Also the receptacle or hopper is positioned alongside of the left leg of the person giving the person's arms and hands freedom from interference by the receptacle also permitting the person to stand upright and bend over without interference from the receptacle or hopper. As asparagus is cut and gathered by the person it may be placed in the receptacle or hopper with the tips of the asparagus engaging the end wall 3. The receptacle or hopper inclining as described maintains the asparagus therein with the tips in engagement with the end wall. The opposite end of the receptacle or hopper being fully open will permit extremely long pieces of the asparagus to be accommodated within the receptacle or hopper and such long pieces may protrude therefrom by way of the open end thereof.

The side walls 4 and 5 of the receptacle or hopper have formed therein aligned slots 11 terminating short of the bottom wall 2 for the purpose of forming a guide for a knife employed for cutting the asparagus to a desired length while stacked in the receptacle or hopper.

The waist belt 10 includes a buckle 12 and an apertured strap 13 to be received by said buckle so that the waist belt may be readily adjusted about and to a person's waist.

In forming the slots 11 the material of the walls 4 and 5 is bent upon itself, as clearly shown in Figure 4, so that said slots will have smooth edges.

The receptacle or hopper constructed in accordance with the foregoing can be easily emptied after being filled with asparagus and after the removal of the waist belt from the person.

What is claimed is:

1. An asparagus gathering device comprising a receptacle open at its top and at one end, means for supporting said receptacle obliquely on a person with its closed end disposed lower than the said open end so that asparagus placed in the receptacle will stack therein against the lowermost closed end of the receptacle.

2. An asparagus gathering device comprising a receptacle open at its top and at one end, means for supporting said receptacle obliquely on a person with one of its ends disposed lowermost and to one side of the person so that aspar-

50

55

agus placed in the receptacle will stack therein against the lowermost end of the receptacle, said receptacle having slots in opposite walls to form a guide for a knife to permit severing of the asparagus in the receptacle to a desired length.

3. An asparagus gathering device comprising a receptacle including a rounded bottom, an end wall and side walls, a frame having said walls bent thereabout with one end of the frame positioned beyond one end of the receptacle forming a handle means, suspension straps connected to one side of the said frame and one being of a greater length than the other, a waist belt secured to said straps for encircling a person's waist and permitting the receptacle to be positioned at one side of the person with the end wall of the receptacle being disposed lower than the opposite end of the receptacle.

4. An asparagus gathering device comprising a receptacle including a rounded bottom, an end wall and side walls, a frame having said walls bent thereabout with one end of the frame positioned beyond one end of the receptacle to comprise a handle means, suspension straps connected to one side of the said frame and one being of a greater length than the other, a waist belt secured to said straps for encircling a person's waist and permitting the receptacle to be positioned at one side of the person with the end wall of the receptacle being disposed lower than the opposite end of the receptacle, said side walls having aligning slots terminating short of the bottom wall to form a knife guide. 5 10 15
